UNITED STATES PATENT OFFICE.

JOHN DE FREEZE, OF NEWARK, OHIO, ASSIGNOR OF ONE-HALF TO CHARLES B. LUTON,
OF LOWELL, OHIO.

DESIGN FOR A BADGE.

40,683.

Specification for Design.

Patented May 10, 1910.

Application filed March 29, 1910. Serial No. 552,273. Term of patent 7 years.

To all whom it may concern:

Be it known that I, JOHN DE FREEZE, a citizen of the United States, residing at Newark, in the county of Licking and State of Ohio, have invented a new, original, and ornamental Design for Badges, of which the following is a specification, reference being had to the accompanying drawing, forming part thereof.

The figure is a front view of a badge, showing my new design.

I claim:

The ornamental design for a badge, as shown.

JOHN DE FREEZE.
